UNITED STATES PATENT OFFICE.

JAKOB SCHWEIZER, OF SOLEURE, SWITZERLAND.

APPARATUS FOR PRODUCING COMPRESSED AIR.

SPECIFICATION forming part of Letters Patent No. 292,957, dated February 5, 1884.

Application filed March 5, 1883. (No model.) Patented in France January 12, 1883, No. 153,068.

To all whom it may concern:

Be it known that I, JAKOB SCHWEIZER, a citizen of the Republic of Switzerland, and a resident of Soleure, Switzerland, have invented certain Improvements in Apparatus for Compressing Aeriform Fluids, of which the following is a specification.

My invention relates to an apparatus for compressing aeriform fluids by the explosion of a mixture of gas and air at the upper part of the compression-chamber and in direct contact with the fluids to be compressed, no piston being interposed. I introduce inflammable gas to the upper part of a closed chamber, where it mixes with atmospheric air in sufficient quantity to produce an explosive detonating mixture, and then igniting this mixture, whereby the aeriform fluids in the lower part of the closed chamber will be compressed by the expansion produced by the explosion of the supernatant mixture of air and gas. The closed chamber communicates with the reservoir for the compressed aeriform fluids by means of a valved aperture, the valve of which opens into the reservoir. Consequently when the aeriform fluids in the closed chamber are compressed by the explosion they expand into the reservoir. The explosions are successive, and the reservoir is thus kept supplied from the explosion-chamber. In order to prevent the pressure in the reservoir from rising above a predetermined point, means are provided whereby, when the pressure rises above the said point the admission of gas to the explosion-chamber is cut off automatically. In order to bring about successive explosions some suitable mechanism is employed for cutting off the gas-supply intermittently and for effecting the ignition at the proper time. For this purpose I may employ an engine similar to that described and claimed in a pending application of mine, and which I have shown herein.

In the drawings, which serve to illustrate my invention, Figure 1 is a side elevation, the engine-cylinder being in section. Fig. 2 is a sectional plan, the explosion-chamber being in section on line 2 2 in Fig. 1. Fig. 3 is a vertical section on line 3 3 in Fig. 2.

50 A represents the explosion-chamber, which is herein shown as a cylinder mounted on a

reservoir, B, for the compressed fluids. In the partition which separates the chamber A from the reservoir B, is an aperture, C, which is closed or controlled by a valve, C', which opens downward into the reservoir and is upheld normally by a spring.

D is a pipe, which admits inflammable gas to the upper part of the chamber A, its upper end being perforated, to permit the gas to escape and diffuse itself throughout the upper part of the chamber. On the side of the chamber A is mounted a seat, H, for the cut-off valves E and F. This seat has a gas-passage, e, which communicates at its inner end with the pipe D and at its outer end with the gas-supply pipe d. The horizontal slide-valve E has a cross-port, b, which may be brought into and moved out of coincidence with the passage e by suitable mechanism that will be hereinafter described, so as to admit the inflammable gas to chamber A intermittently. The vertical slide-valve F has a port, c, and is in general constructed the same as valve E. This valve rests on a packed piston, F', in a provision on the reservoir B, and is arranged under a weighted lever, G, fulcrumed on the cylinder A. When the pressure in the reservoir B increases beyond the point desired, the compressed fluid acts upon the piston F' to raise it, and thus move the valve F high enough to close the gas-passage e. This of course stops the explosions, and this stoppage will continue until the pressure in the reservoir falls and the passage e is again opened. The desired tension in the reservoir is attained by shifting the weight in or out on lever G.

I will now describe the mechanism which I have shown, and which I prefer to employ for effecting the successive explosions in the chamber A. This engine I do not claim specifically herein.

Mounted on the reservoir B is a suitable bed-plate or frame, G', upon which is fixed the engine-cylinder K. The piston K' in this cylinder is coupled, by a piston-rod, p, and connecting-rod l, with a crank in the main shaft O. On this shaft is mounted a fly-wheel, V, and a crank, l'. The latter crank is coupled by a connecting-rod, k, to a horizontal slide-valve, E. Thus it will be seen that reciprocation of the piston K' produces rota-

tion of the shaft O and reciprocation of the valve E. The engine belongs to the class known as "single-acting," and the piston receives its impulses from the compressed fluids in the lower part of chamber A through a pipe, q. This pipe taps a dome, O', in the top of the engine-cylinder, and a valve, q', in said dome acts as a check-valve to prevent any reflex action of the compressed fluids.

10 I will now digress to describe the igniting mechanism.

From the gas-passage e, suitable pipes lead gas to two gas-jets, g and g'. The latter jet is merely a relighting-jet, and its functions will 15 be described hereinafter. The jet g is directed toward an aperture, I, in the upper part of the chamber A, which aperture is closed by a pendent clack-valve, J, which opens inwardly.

10 I will now describe the operation whereby 20 the fluids are compressed and stored in the reservoir B.

The jet g is lighted, and we will suppose that the piston K' stands at the upper end of the cylinder K, and the valve E stands in a position to leave the gas-passage e open. The 25 gas enters through D and mixes with the air in the upper part of the chamber A to an extent sufficient to form an explosive compound. The fly-wheel V is now rotated a little way by 30 hand, which has the effect to close the gas-passage e by the movement of the valve E; but it also has the effect, by the descent of the piston K', to produce a partial vacuum in the chamber A, whereby air is drawn in through 35 the aperture I. This draws or sucks in the flame of the jet g, which instantly ignites the explosive mixture of air and gas in the upper part of A. This explosion suddenly closes the valve J and compresses the aeriform fluid 40 in the lower part of chamber A; but as the valve C' opens downward the compressed fluid depresses this valve and passes into reservoir B until an equilibrium is established between A and B. When the explosion takes place, 45 however, a portion of the compressed fluid in the lower part of A, acts through pipe q to force the piston K' down, and this, with sufficient impetus to cause the crank to which it is coupled to pass the center, aided by the fly- 50 wheel V, and to cause the piston to again rise to the top of the cylinder. In order to allow the piston to rise, a suitable slide-valve, B', as shown in Fig. 2, is provided to control the exhaust. This valve may be actuated by an 55 eccentric on the shaft O. Thus each explosion causes one revolution of the shaft O, and of course the intermittent successive explosions will keep the shaft revolving. This constant motion of the engine will admit inter- 60 mittent supplies of inflammable gas and air to chamber A, and by the movement of the piston produce successive ignitions. When the valve J is suddenly closed by the explosion the jet g is apt to be extinguished; there- 65 fore I supply the relighting-jet g'; arranged as shown in Fig. 3.

The compressed aeriform fluids in the reservoir B may be employed for any purpose, and may be supplied through the pipe h. The gas supplied to the jets may be regulated by 70 cocks f f.

In lieu of the engine described for actuating the valve E, some other form of engine may be employed; and, in order to effect the rarefaction in the chamber A, whereby air to form 75 the explosive mixture is drawn in, and also flame from jet g to ignite the gases, a small suction-pump or ordinary air-exhausting device may be employed. These may be run by the compressed fluids in B. I do not deem it 80 necessary to describe every form of engine that may be employed for this purpose. As the explosion-chamber A is at the beginning filled with atmospheric air, it will be obvious that the first explosion will force the air in 85 the lower part of the chamber down into B; but after the first explosion and as long as these are kept up continuously the lower part of chamber A will contain aeriform fluids composed mainly of "burned gases," so called, 90 or products of combustion—that is to say, mainly nitrogen and carbonic acid. The air enters A only at I, and mixes at once with the inflammable gas admitted through pipe D, thus forming an explosive mixture which 95 is at once ignited.

I am aware that it is not new to compress air by the explosion of gas; but so far as I am aware the air compressed has always been separated from the explosive gases by a piston, 100 and the products of combustion are got rid of by special means. I do not employ any piston, but simply effect the explosion in the upper part of a closed vessel containing aeriform fluids. Thus the products of combustion 105 are themselves compressed and utilized.

Having thus described my invention, I claim—

1. In an apparatus for compressing aeriform fluids, the combination of the explosion-chamber, provided with a valved aperture to admit air at its upper part, the gas-supply pipe, arranged as shown, and the valve aperture opening into the reservoir for the compressed fluids, the said reservoir provided 110 with the piston F', the valve F, the weighted lever G, the valve E, the jet g, and means, substantially as described, for actuating the valve E and for causing the flame g to enter the explosion-chamber and ignite the gases therein, 115 all arranged to operate substantially as set forth.

2. The combination, in an apparatus for compressing aeriform fluids, of the upright explosion-chamber A, provided with a valved aperture, I, at its upper part, for the admission of air, and a valved aperture, C, at its lower part, for the passage of the compressed fluids to the reservoir B, the gas-supply pipe D, with its upper end perforated and arranged 125 in the upper part of the explosion-chamber A, the reservoir B, the jet g, and means, substan- 130

tially as described, for regulating the influx of gas and air to the explosion-chamber, whereby the explosion in the upper part of chamber A effects the compression of the fluids in the lower part of said chamber without the intermediation of the piston, substantially as set forth.

In witness whereof I have hereunto signed my name in the presence of two subscribing witnesses.

JAKOB SCHWEIZER.
